UNITED STATES PATENT OFFICE.

GEORGE W. DONNING, OF STAMFORD, CONNECTICUT, ASSIGNOR TO DONNING CARBURETER CORPORATION, OF ESOPUS, NEW YORK, A CORPORATION OF NEW YORK.

CARBURETER.

1,269,689.

Specification of Letters Patent. Patented June 18, 1918.

Application filed August 26, 1915. Serial No. 47,531.

To all whom it may concern:

Be it known that I, GEORGE W. DONNING, a citizen of the United States, residing at Stamford, in the county of Fairfield and 5 State of Connecticut, have invented certain new and useful Improvements in Carbureters, of which the following is a specification, reference being had therein to the accompanying drawing.

10 This invention relates to carbureters for use, particularly, in connection with internal combustion motors.

15 The object of the invention, in one of its broadest aspects, is to utilize air for heating the walls of a carbureter—and, in certain instances, the motor inlet-manifold—tempered to substantially the same degree as the air which is used for making the gaseous mixture in the carbureter, there being novel 20 means (such as an electric device) provided for controlling the temperature of the air automatically, the electric device being thermostatically controlled.

25 Still another object is to effect the automatic preheating operation in the event that the temperature of the air or of the gaseous mixture should, at any time, fall, even temporarily, below a predetermined point.

30 Still another object within the contemplation of the invention is to provide a thermostatic device, preferably arranged in the path or effective zone of the heating fluid, and which will not only control the temperature of the air, but also render the air-preheater active or inactive and, moreover, effect an operation of valves which control various air ports; such device being adjustable so that different temperatures may be selected to accord with different grades of 35 fuel that may be used, with consequent economy in the employment of the same.

40 A further object of the invention is to provide means for releasing, into the atmosphere, the heated air (or portions thereof) before it reaches the carbureter chamber, in accordance with the requirements of the motor.

45 The invention in general seeks to provide a structure in which the various instrumentalities have a certainty of action to accomplish the required results, and which structure, from an operative standpoint, is effectual at all times and which structurally considered, is simple and compact and, while

functioning, requires little if any regulating.

55 Other objects and advantages of the invention will be more or less apparent from the appended drawings and will be made entirely clear from the following description.

60 In order that the invention may be readily comprehended, drawings are hereto appended and which are illustrative of a preferred embodiment of the invention; it being understood, however, that the same is capable 65 of a wide range of modification and is susceptible of utilizations different from that revealed.

65 In the drawings:

70 Figure 1 is a view in vertical section of a carbureter constructed in accordance with one embodiment of my invention;

75 Fig. 1^a is a similar view of a modified form of structure, the same being constructed in accordance with a somewhat different embodiment of the invention, and in which the heating-device in the air-conduit occupies a different position than in Fig. 1;

80 Fig. 2 is a fragmentary view of a modified form of air-intake structure;

85 Fig. 3 is a fragmentary view of a modified form of air and controlling device; and

Fig. 4 is a collective view in detail of parts of the air and controlling device.

90 Referring to the drawings, it will be noted that the reference-character 1 designates the outline of a combustion motor, which may include one or a plurality of cylinders, not shown.

95 Connected with the motor, in any appropriate manner, as by inlet-manifolds 2, is my improved carbureter designated, generally, by the reference-character 3. In this instance, the manifolds are surrounded by a jacket 4 which provides a channel 5 adapted to contain a heating fluid which, in this instance, is air. The channel is supplied with heating fluid from a source and in a manner presently to be explained.

100 Preferably and as shown, the carbureter includes a mixing chamber 6 and an air-chamber 7. These chambers are separated by a corrugated valve-member 8 which, being of thin resilient metal, is flexible and adapted to seat upon a circumferential ridge 105 9 extending inwardly from the walls of the carbureter. The plate 8 is provided with a

series of apertures 10, as shown. Depending from the plate is a fuel-controlling valve 11 forming an extension of a stem 12 which carries a pin 13 adapted to engage in a slot 14 formed in a movable arm 15 pivoted on a slide member 16. As shown, this slide member extends through the wall of the carbureter, projects beyond the exterior surface thereof, and carries a knurled head 17. By 10 this slide, an adjustment of the arm 15 may be effected.

The arm 15 is sustained in a normally horizontal position by being attached to a link 18 pivotally connected to a throttle-valve 19 which, in turn, is pivoted at 20. The valve is positionable by any preferred means, and which may be those usually employed in this type of structure. By adjusting the arm 15 through the slide-member 16, the fulcrum of the arm is shifted toward the right or left, whereby the position of the fulcrum of the link 18 may be changed and, thus, the extent of movement of the valves 8 and 11 may be varied.

25 Mounted in and upstanding from the bottom-portion 21 of the carbureter is a fuel nozzle 22 provided with a passage 23 in which the valve 11 is adapted to be seated to control the same. This nozzle is encompassed by a relatively stationary member 24, preferably constructed of insulating material. Encircling the nozzle 22 and housed by the encompassing member 24 is an electric heating coil 25 to which electric conducting wires 26 and 27 are connected, the latter being at times energized by a battery, presently to be described. The stationary member 24 may be made integral with the nozzle 22 and, in such instance, the heating coil would be omitted. The encompassing member 24 is adapted to receive any fuel that may have overflowed from the discharge end of the nozzle and not become gasified and carried up into the carbureter or 40 mixing chamber 6, such fuel atomized in the chamber 7, this being effected by the air which passes over the surface of the member 24 and, also, by the heat generated by the coil 25.

50 It will be understood that by means of the valves 8 and 11, both the amount of the air and the amount of the fuel introduced into the mixing-chamber 6 may simultaneously be regulated, since both valves depend 55 for their movement upon the actuation of the arm 15 which is controlled by the throttle-valve 19, as already explained. Therefore, when the fuel is completely arrested by the valve 11, the air will be blocked 60 against entrance into the mixing chamber 6 by the valve 8, since it will be seated on the ridge 9. The formation of the holes 10 in the valve-plate 8 is desirable but not essential, since the flexibility of the plate 8 65 will permit a slight raising of the periph-

eral portions of the plate from the ridge 9, if the air-pressure against the plate caused by suction be sufficient.

The elongated formation of the valve 11 and of the walls of the passage 23 permit 70 an exact adjustment thereof. As shown in Fig. 1, for instance, the passage 23 is enlarged to form a chamber 28. Below this chamber 28 is a passage 29 in which a cylindrical portion 30 of the valve 11 is guided. 75 The chamber 28 provides for the storage of a small quantity of fuel which may be heated by the electric heater 25. Leading into the chamber 28 are channels 28^a through which fuel flows thereinto from below.

80 Threaded into the nozzle 22 is a Y-coupling 31 adapted to be connected to sources of different grades of fuel, and permits the use of gasoline or kerosene, or both mixed. To this end, a valve 31^a is disposed in the 85 coupling, its construction being such (as shown) that the fuel may flow through its Y-shaped channel from one arm of the Y-coupling, or from the other arm, or from both.

85 Opening into the mixing-chamber 6 is an auxiliary air-port 32 that is controlled by a spring-pressed valve 33.

90 Mounted in the upper portion of the carbureter and preferably in the path of flow 95 of the gaseous mixture from the mixing-chamber 6 into the manifolds 3 is a casing 34 containing a volatile liquid 35. The casing is provided with a cap 36 which has a separable pendant, tubular portion 37. Between the inner surface of the wall of the casing 34 and the exterior surface of the tubular portion 37 is a space 38 in which air may be stored. Projecting through the cap 36 and into the casing 34, and having a 100 sliding engagement with the tubular portion 37, is a plunger 39 that may, as shown, be provided with grooves 40 which, when filled with graphite or a similar material, 105 will prevent leakage.

110 The cap 36 is threaded into the carbureter and packing (not shown) may be held thereby to prevent leakage. The upper and exposed portion of the plunger is, as shown, provided with a series of recesses or holes 115 42, corresponding to temperature-graduations and into which may be inserted pins 43 and 44. A pointer 45 on the cap 36 registers with one or another of the aforementioned temperature-graduations as the 120 plunger 39 moves up or down.

125 The heated gaseous mixture, as it passes from the carbureting chamber 6 to the manifolds 3, effects a heating of the contents 35 of the casing 34 and, due to the expansion 125 of such contents, the plunger 39 will be raised and vice versa when such contents cool.

130 Upstanding from the top-portion 46 of the carbureter is a standard 47. Pivoted 130

thereon is a swinging, spring-pressed arm 48 (Figs. 1 and 1^a) which is adapted to underlie and be actuated by the pin 44 on the plunger 39, and which restricts the upward movement of the arm 48. On the standard 47 and in the path of movement of the arm 48 is a terminal 49 to which a wire 50 is connected and which in turn is connected to a combined switch-device and rheostat 51. Connected to a terminal on the arm 48 is a second wire 52 which extends to an electric battery 53.

Also pivoted on the standard 47 is a lever 54 adapted to be engaged by the pin 43 in the plunger 39, and which is held against the pin 43 by a spring 55, the tension of which may be controlled by a tensioning-device 56. Pivoted to the lever 54 is an actuating rod 57 which, at its other end, is connected to a valve-member 58.

Formed in the carbureter and in juxtaposition to the mixing-chamber 6, the thermostatic-casing 34 and the air-chamber 7 are channels 61, and 63 preferably communicating with the channels 5 formed in the walls of the intake-manifolds, and into these channels air from an air-conduit (presently to be described) is introduced and the temperature of which is influenced—raised, for instance—by the tempered air passing into the chamber from said air-conduit.

To protect these channels from extreme heat or cold, I may incase the carbureter-walls, etc., with a covering 64 of asbestos or the like. To protect the asbestos from injury, a metallic casing 65 (Fig. 1) may be utilized.

The lower, angular portion 66 of the carbureter, forming a part of the air-chamber 7, is provided with a plurality of air-ports 67, 68 and 69, which are controlled, respectively, by the valve-member 58, formed of a plurality of cover-elements 71 and 72 and controlled by the actuating rod 57. The air-port 68, as shown, is formed by an air intake extension of the portion 66 and is adapted to introduce into the carbureter air drawn from the atmosphere.

Connected with the air-port 69 is an air-conduit (Fig. 1) which may be protected, as by a metallic and asbestos casing 74 as shown, fragmentary, at the right-hand end of the conduit.

The lower portion of the carbureter is provided with an opening 75 to receive heated air which is adapted to circulate into the channels aforementioned.

Suspended in the air-conduit is a heating-coil 76 and to this are connected, as by wires 77 and 78, the terminals 79 and 80. Connecting the terminals 79 with the switch-device 51 is a conducting wire 81. Connecting the terminal 80 and the battery 53 is a conducting wire 83. Between the switch-device 51 and the terminal 49, on the con-

ducting wire 50, is a signal light 84. The aforementioned conducting wire 26 is connected with the wire 81, while the wire 27 is connected with the wire 83. Between the ends of the heating-coil 76 is interposed a terminal 82. When the wire 81^a is detached from the terminal 79 and attached to the terminal 82, only a portion of the coil will be energized when the current is on, thus enabling one to vary the heating capacity of the air-conduit.

Mounted at the end of the air-conduit 73, and extending in alinement with or below the plane of the air-chamber 7, is an air-heater 85 provided with an air-inlet 86 and encompassing a portion of the exhaust-manifold 87, whereby the contained air may be heated.

Operation: Assuming that the switch-device 51 is on and that the carbureter is cold, the plunger 39 of the thermostatic device will be in its lowermost position; hence the arm 48 will be in contact with the terminal 49, completing the circuit through the wires 50 and 52, the battery, heating coil, etc., whereupon said heating coil will be energized and generate heat in the air-conduit. Incidentally, also, the signal light will be lighted and this will indicate to the driver that the parts are performing their proper functions. The moment that the air in the air-conduit and the channels communicating therewith, the mixing-chamber, etc., and the mixture have become sufficiently heated, the plunger 39 will be raised by the expansion of the volatile fluid 35. This will permit the arm 48 to be rocked out of contact with the terminal 49 by its spring, breaking the circuit, whereupon the signal or light and the heating coil will become inactive. At the same time, the lever 54 will be raised by the plunger and this will cause the actuating rod 57 to operate the valve device to open both ports 67 and 68, thereby partially or completely checking the flow of air passing through the conduit 69. While the lever 54 may at times be operated manually, it generally is under the control of the thermostat plunger. The time and extent of operation, with relation to the temperature of the contents of the carbureter, may be predetermined by the driver according to which of the holes 42 contains the pins 43 and 44. For instance, if the pin 43 is inserted in that hole 42 which is below the one in which it is now shown, obviously, the plunger 39 will have a longer movement before it positions the pin against the lever 54; hence, the rod 57 and the valve 58 will not be operated as quickly, wherefore, the temperature of the air passing through the air-conduit will increase and influence the contents of the casing 34 and cause the plunger 39 to have the longer movement just referred to. When these are once adjusted by the driver for

115
120
125
130

any of a plurality of fuels, they may permanently be left adjusted so that, winter or summer, or during sudden changes of the atmosphere, there is no need for adjustments to meet such atmospheric changes.

In a co-pending application, Serial No. 863,369, filed Sept. 24, 1914, by me and others, valve mechanism is shown for partly or completely cutting off the hot or cold air from either of two ports. In the present structure, and as illustrated in Fig. 1, three ports are disclosed. The advantage of the third port is that when it is opened, some of the air heated in the air conduit will escape through the port 67 into the atmosphere. Moreover, the incoming air tends to cool the heated air in the conduit. The cooler, outside air would, in the structure of said co-pending application, tend to cool the carbureter, itself; or, if one of the ports is partly open, or the metal of the carbureter becomes too hot, air of too high temperature may be admitted to the mixing-chamber with a consequent over-heating of the mixture.

In Fig. 2, I have shown a somewhat modified form of construction: In this instance, the valve-actuating rod 57 is pivoted to a two-membered valve-device 88, one part of which controls the port 89 while the other controls the port 90. When the valve-device is in the position it assumes, when tilted, the ports 89 and 90 will be opened, while the passage of air through the conduit at the right hand side of the valve device 88 will thereby be cut off to permit air to flow into the conduit through the port 89.

In Figs. 3 and 4, I have shown a modified form of air and fuel-controlling device disposed between the mixing-chamber 6 and the air-chamber 7. This includes a disk 91 adapted to be seated upon a circumferential ridge or seat 9. The disk 91 is connected to but has a movement independent of a plate 93 and is maintained in yieldable relation thereto by a three-armed member 94 of resilient material which is, itself, carried by a valve-stem 95 supported by an arm 96 which is of the construction and has the operation described with reference to the form of device shown in Fig. 1. The disk 91 is provided with lugs or posts 97. The disk 91 is formed with a central opening 98 and is normally held yieldingly in its seat 92 by the resilient arms of the member 94, so that a passage is left as at 98, the lugs 97 maintaining a spaced relation of the disk 91 from the member 94. When the arm 96 is lowered, the disk 91 and the member 94 are permitted to come into engagement. When, however, the arm 96 is raised, the member 94 may have a slight movement away from the disk 91. Then, only a considerable suction of the motor will raise the disk 91 again into engagement with the member 94.

Herein, I regard the electric air-heater, or the electric fuel-heater, or both, as primary or initial heaters, while the exhaust-heater 85 may be regarded as a secondary heater. In extremely cold weather, or when the temperature is liable to sudden changes—for example, in aeroplanes, motor-boats, etc.—the exhaust-heater is not always, of itself, capable of producing sufficient heat. In that event, the electric heater or heaters, in my structure, will automatically become operative due to the operation of the thermostatic device which, becoming cool, will actuate the ports and will control the activity of the heating coil in the air-conduit. 30

By this invention, the effort has been made to develop a carbureter which embodies, as permanent parts, certain heating and cooling instrumentalities heretofore regarded as seasonal attachments; and, thereby, a carbureter is produced which is not variable, due to the variability of atmospheric and other conditions. 35

My structures are peculiarly adapted to reduce, to a minimum, the possibility of fires. 90 In the event that the carbureter should be fired, it is only necessary to release the throttle-control and permit the fuel-valve (and the parts controlled thereby) to engage its seat and thereby cut off the flow of fuel 95 into the carbureter, whereupon the flame would be snuffed out.

From the foregoing, it will be seen that I have devised a carbureter which is well adapted to achieve the objects and ends in view. The structure is exceedingly simple and compact in form and is particularly well suited for automobiles.

As many changes can be made in the above construction and many other embodiments of the invention can be made without departing from the spirit thereof, it is intended that all matter contained in the foregoing description and shown in the accompanying drawings shall be interpreted as 110 illustrative and not in a limiting sense except as limitations are expressed in the claims.

What I claim is:

1. A carbureter including a chamber provided with an air-inlet and a mixture-outlet, means independent of the carbureter-chamber for heating air passing into the carbureter, and a jacket surrounding the chamber to provide a channel between the chamber 115 and the jacket and closed against the chamber for housing a body of air independent of the air introduced into the chamber and means within the chamber and influenced by its contents for controlling the temperature 120 of the air entering the channel whereby overheating of the chamber by the heated air in the channel is prevented.

2. A carbureter including a chamber provided with an air-inlet and a mixture-outlet, 125

means independent of the carbureter-chamber for heating air passing into the carbureter, a jacket surrounding the chamber to provide a channel between the chamber and the jacket and closed against the chamber for housing a body of air independent of the air introduced into the chamber, means within the chamber and influenced by its contents for controlling the temperature of the air entering the channel whereby overheating of the chamber by the heated air in the channel is prevented, and an intake-manifold provided with channelled walls, the channel thereof communicating with the channel surrounding the carbureter-chamber.

3. A carbureter including a chamber provided with an air-inlet and a mixture-outlet, and means independent of the carbureter-chamber for heating air passing into the carbureter, a jacket surrounding the chamber to provide a channel between the chamber and the jacket for containing a body of air independent of the air introduced into the chamber, a temperature-controlling means within the chamber and influenced by the contents thereof to govern the temperature of the air passing into the carbureter, and an intake-manifold provided with a channel in its walls which communicates with the channel surrounding the carbureter-chamber.

4. A carbureter including a plurality of chambers, an air-jacket surrounding one of the chambers, valve-mechanism for controlling the flow of air between the chambers, an air-conduit communicating with one of the chambers and with the jacket, and a plurality of independently operable heating means within the air-conduit for heating air at different points therein and for influencing the temperature of the air in the jacket.

5. A carbureter including a mixing-chamber and an air-chamber, valve-mechanism between the chambers for controlling the flow of air from the latter to the former, an air-jacket disposed about the mixing-chamber, an air-conduit communicating with the air-chamber and with the jacket, heating means within the air-conduit, and a second heating means adjacent one end of the conduit for heating air preliminary to its passing into the air-chamber; said valve-mechanism operating, when in its closed position, to hold a portion of the air temporarily in the air-chamber; said heating means being effective to heat the air before it passes into the air-chamber, and, also, acting to influence the temperature of the air in the air-jacket.

6. A carbureter including a mixing-chamber and an air-chamber, valve mechanism between the chambers for controlling the flow of air from the latter to the former, an air-jacket disposed about the mixing-chamber, an air-conduit communicating with the air-

chamber and with the jacket, heating means within the air-conduit, a second heating means adjacent one end of the conduit for heating air preliminary to its passing into the air-chamber; said valve-mechanism operating, when in its closed position, to hold a portion of the air temporarily in the air-chamber; said heating means being effective to heat the air before it passes into the air-chamber and, also, acting to influence the temperature of the air in the air-jacket; said air-conduit being provided with at least three ports; and valve-mechanism for controlling the passage of air through the air-conduit and through two of the ports therein. 30

7. A carbureter including a mixing-chamber, a mixture-outlet, an air-chamber, valve-mechanism between the chambers for controlling the flow of air from the latter to the former, an air-jacket disposed about the mixing-chamber, an air-heating means within the air-conduit, a second heating means adjacent one end of the conduit for heating air preliminary to its passing into the air-chamber; said valve-mechanism operating, when in its closed position, to hold a portion of the air temporarily in the air-chamber; said heating means being effective to heat the air before it passes into the air-chamber and, also, acting to influence the 95 temperature of the air in the air-jacket; said air-conduit being provided with at least three ports; valve-mechanism for controlling the passage of air through the air-conduit and through two of the ports therein, 100 and valve-actuating mechanism acting under the influence of the temperature of the mixture which passes through the mixture-outlet for operating the valve-mechanism of the air-conduit.

8. A carbureter including a mixing-chamber, a mixture-outlet, an air-chamber, valve-mechanism between the chambers for controlling the flow of air from the latter to the former, an air-jacket disposed about the mixing-chamber, an air-heating means within the air-conduit, a second heating means adjacent one end of the conduit for heating air preliminary to its passing into the air-chamber; said valve-mechanism operating, 110 when in its closed position, to hold a portion of the air temporarily in the air-chamber; said heating means being effective to heat the air before it passes into the air-chamber and, also, acting to influence the 115 temperature of the air in the air-jacket; said air-conduit being provided with at least three ports; valve-mechanism for controlling the passage of air through the air-conduit and through two of the ports therein, 120 and valve-actuating mechanism acting under the influence of the temperature of the mixture which passes through the mixture-outlet for operating the valve-mechanism of the air-conduit and comprising a 125 130

thermostatic device extending into the carbureter.

9. A carbureter-structure including a mixing-chamber, an air-conduit communicating with the chamber and provided with a plurality of ports, valve-mechanism including closing elements for two of the ports and operable to close said air-conduit against the passage of air into the chamber through a portion of the conduit and at the same time opening at least two of the ports for the inflow of air through one of the ports from the outside into the air-conduit and chamber and for the outflow of air from a portion of the conduit through another of the ports into the outside atmosphere and means for heating the contents of the air-conduit.

10. A carbureter-structure including a mixing-chamber, an air-conduit communicating with the chamber and provided with a plurality of ports, valve-mechanism including closing elements for two of the ports and operable to close said air-conduit against the passage of air into the chamber through a portion of the conduit and at the same time opening at least two of the ports for the inflow of air through one of the ports from the outside into the air-conduit and chamber and for the outflow of air from a portion of the conduit through another of the ports into the outside atmosphere, means for operating said valve-mechanism and means for heating the contents of the air-conduit.

11. A carbureter-structure including a mixing-chamber, an air-conduit communicating with the chamber and provided with a plurality of ports, valve-mechanism including closing elements for two of the ports and operable for closing said air-conduit against the passage of air into the chamber through a portion of the conduit and at the same time opening at least two of the ports for the inflow of air through one of the ports from the outside into the air-conduit and chamber and for the outflow of air from a portion of the conduit through another of the ports into the outside atmosphere, means for operating said valve-mechanism including a thermostatic device adjacent to and influenced by the temperature of the contents of the chamber and means for heating the contents of the air-conduit.

12. A carbureter-structure including a mixing-chamber, an air-conduit communicating with the chamber and provided with a plurality of ports, valve-mechanism including closing elements for two of the ports and operable for closing said air-conduit against the passage of air into the chamber through a portion of the conduit and at the same time opening at least two of the ports for the inflow of air through one of the ports from the outside into the

air-conduit and chamber and for the outflow of air from a portion of the conduit through another of the ports into the outside atmosphere, means for operating said valve-mechanism including a thermostatic device adjacent to and influenced by the temperature of the contents of the chamber, means for heating the air in the conduit, and means disposed between the thermostatic device and the conduit whereby the former controls the temperature of the latter.

13. A carbureter including a mixing-chamber, an air-chamber, valve-mechanism interposed between the chambers for controlling the flow of air from said air-chamber into said mixing-chamber, a channel formed around the chambers, an air-conduit communicating with the air-chamber, heating means within the air-conduit, said air-conduit being provided with three ports, and valve-mechanism common to two of the three ports for controlling the same and operable to close the conduit at one side of one of the ports.

14. A carbureter including a mixing-chamber, an air-chamber, valve-mechanism interposed between the chambers for controlling the flow of air from said air-chamber into said mixing-chamber, a channel formed around the chambers, an air-conduit communicating with the air-chamber, heating means within the air-conduit, said air-conduit being provided with three ports, valve-mechanism common to two of the three ports for controlling the same and operable to close the conduit at one side of one of the ports, and mechanism acting under the influence of the temperature of the contents of the carbureter for actuating said valve-mechanism.

15. A carbureter including a mixing-chamber, an air-chamber, valve-mechanism interposed between the chambers for controlling the flow of air from said air-chamber into said mixing-chamber, a channel formed around the chambers, an air-conduit communicating with the air-chamber, heating means within the air-conduit, said air-conduit being provided with three ports, valve-mechanism common to two of the three ports for controlling the same, and means comprising a thermostatic device housed entirely within the carbureter and acting under the influence of the temperature of its contents for actuating said valve-mechanism and operable to close the conduit at one side of one of the ports.

16. A carbureter having a chamber, a throttle-valve therein, air and fuel-controlling valves in the chamber, an air-conduit communicating with the carbureter chamber and provided with a plurality of ports, a heating device within the air-conduit for heating air passing to and beyond the controlling valve, valve-mechanism for control-

- ling the passage of air through said air-conduit and through the ports and operable to close the conduit against passage of air and simultaneously to permit the flow of 5 air through at least one of said ports, means including a thermostatic device disposed within the carbureter chamber and influenced by the temperature of the contents therein for controlling the temperature of 10 the contents of the air-conduit previous to passing said controlling valves, resilient means operative on said temperature-controlling means and tending to overcome the influencing action of the thermostatic device, and means for rendering said resilient 15 means active.
17. A carbureter including a chamber, a throttle-valve therein, air and fuel-controlling valves in the chamber, an air-conduit 20 communicating with the carbureter chamber, a heating device within the air-conduit for heating air passing to and beyond the controlling valve, means including a thermostatic device disposed within the carbureter 25 chamber and influenced by the temperature of the contents therein for controlling the temperature of the contents of the air-conduit previous to passing said controlling valves, resilient means operative on said
- temperature-controlling means and tending to overcome the influencing action of the thermostatic device, means for rendering said resilient means active, and a valve for controlling flow of fluid into the nozzle and operatively connected to said resilient means 30 whereby operation of the valve effects a tensioning of the resilient means.
18. A carbureter including a chamber, fuel-controlling means for governing the flow of fuel thereinto, an air-inlet communicating with the chamber and provided with a port, a valve controlling the port, a thermostatic device influenced by the temperature of the contents of the chamber, a counteracting-device adjacent the port-controlling valve and tending to influence the action of the thermostatic device, and a connection between the counteracting-device 40 and the fuel-controlling means whereby operation of the counteracting device sets 45 the fuel-controlling means.

In testimony whereof I affix my signature in presence of two witnesses.

GEORGE W. DONNING.
